UNITED STATES PATENT OFFICE.

ALEXANDER S. SPIEGEL, OF CHICAGO, ILLINOIS.

MEANS FOR APPLYING COLORED DESIGNS TO COMPOSITION ROOFING.

1,082,364.

Specification of Letters Patent.

Patented Dec. 23, 1913.

Application filed November 19, 1912. Serial No. 732,328.

To all whom it may concern:

Be it known that I, ALEXANDER S. SPIEGEL, citizen of the United States, residing at Chicago, Illinois, have invented certain new and useful Improvements in Means for Applying Colored Designs to Composition Roofing, of which the following is a specification.

It is well known that in the manufacture and production of composition roofing using an asphalt surface, that it is very desirable to break up the monotony of the appearance of the asphaltum covering by imparting to the surface a design in colors, and it is my 10 aim, by the present device, to accomplish this in a simple and effective manner, making the colors durable and permanent. I utilize the roofing as it is now made, and apply to the asphaltum coating grit or sand 15 colored in any suitable manner so as to form a permanent carrier or vehicle, the sand being fed to the surface of the roofing through feeding mechanism which applies the differently colored sand or grit in attractive 20 designs upon the asphaltum surface.

I have designed an improved machine for applying the colored sand or grit to the surface of the roofing and this, as will be more particularly hereinafter described, includes a structure of general cylindrical 30 shape having rotary movement to and over a part of the periphery of which the composition roofing passes, and in passing receives the colored grit or sand in designs 35 upon its surface, the designs being formed by the structure through a series of pockets to which the material is fed, these pockets being made in any desired form or shape. The roofing covered with asphaltum forms an 40 adherent surface to receive the grit or sand and also closes the bottom of the pockets as it passes around the periphery of the cylindrical structure so that there is no inter-mixture of the differently colored material.

45 In the accompanying drawings, Figure 1 is a diagrammatic view of the end of the cylindrical structure showing the feeding trough for the differently colored materials, the means for rotating the cylinder and the 50 relation of the roofing material to the cylinder showing it as it passes to and from the same. Fig. 2 is a longitudinal section of the machine. Fig. 3 shows a part of the periphery illustrating the pattern means. 55 Fig. 4 shows the completed article. Fig. 5 is a detail of the pattern means.

The cylinder A is suitably supported in

end frames and this frame is rotated through a gear 1, meshing with a rack 2. The composition roofing B with its asphalt coating 60 passes over the roller α and is of a width as shown in Fig. 2, to pass between the end frames 3, 4, of the machine, being supported by rollers 5, 6, and in close contact with the periphery of the cylinder, and the pattern 65 means forming the design upon the surface of the coating, this pattern means consisting of plates or castings c , having the peculiar formation shown in Figs. 2, 3 and 5. Two of the sections c are brought together, 70 suitably secured and supported by rods 7 bolted to the end frames. The peripheral extremities of the sections c are of zig zag shape and the walls of the zig zag portion are inclined inwardly and two of the sections 75 together form practically the shape of a diamond at their extreme periphery while the inclined walls form a hopper through which the sand or grit passes to the surface of the roofing which is inclosed within the 80 margin of the diamond or other shaped opening formed by the sections. It will be observed that the sections c may be shaped at their extremities according to the character of the design or pattern which may be 85 desired on the surface of the roofing and I have only shown the diamond shape as illustrating one form of design.

It will be observed in Fig. 2 that by supporting the end of the roofing material on 90 a margin of the frame 3 an uncoated lap is left on the margin of the roofing, as also shown at 8 in Fig. 4. I feed the colored sand or grit or other material through the hopper C which is divided by a partition 9 for 95 two colors and I provide feeding means in the form of a spiral screw 10 on a shaft 11 driven by a pulley 12, there being one of these feeding devices for each compartment within the hopper, the hopper terminating 100 in a cylinder C' and the feeding mechanism being located in this cylindrical part. The cylinder C' has openings on one side of the partition which are in line with the openings formed by two adjacent sections c and this 105 opening is provided with a slide valve 13 which may be utilized to adjust the size of the opening or close it altogether. Just above the opening or adjacent thereto I locate a corrugated feed roller 14, which feeds 110 the sand or grit through the opening and down through between adjacent sections c to the surface of the composition roofing which closes the diamond or other shaped

opening formed by the adjacent sections. Upon the opposite side of the partition there is another opening in line with the next pair of sections *c* with a like feed roller, and this 5 roller feeds to the surface of the composition roofing a different colored material. In the size of the machine illustrated in the drawing I utilize a full sized opening on one side of the partition with two half sized 10 openings, and on the opposite side of the partition *g*, alternately placed, there are two full sized openings, and this will produce the pattern shown in Fig. 4. The roofing passes around the cylinder while its 15 asphalted surface is hot and adhesive, and hence the sand or grit readily adheres. Any surplus sand will fall off of its own weight as the roller passes over *b*. In order to prevent adhesion of the particles to the frame 20 of the machine I utilize rollers *h* to which may be fed kerosene or the like, and this will keep the machine free from the tendency of particles of the asphalt or grit to adhere. Any desired number of partitions 25 may be utilized according to the number of colors which are to be used.

I claim as my invention:—

1. In combination with supporting means 30 for composition roofing, means for applying to said roofing a colored pattern or design arranged intermediate of the supports for the roofing, comprising a cylindrical rotating device having a skeleton periphery made up of open sections terminating in the 35 form of design to be applied to the roofing, with openings to the interior, and means for feeding different colored sand or grit to the different design sections from the interior of the cylinder, the roofing forming the bottom 40 of the open sections, substantially as described.

2. In combination with supporting means 45 for composition roofing, a skeleton cylindrical section interposed between the supporting means and adapted to receive the composition roofing around a portion of its periphery, the said periphery constituting a series of open designs in outline, and having passages leading to the interior, with 50 feeding means for supplying one color to one or more sections, and for supplying another color to other sections so as to alternate or vary the pattern, the roofing forming the bottom of all the design sections and adapted to receive the sand or grit 55 upon its adhesive surface from the interior, substantially as described.

3. In combination with a series of partitions terminating in open-ended designs 60 forming a skeleton cylinder, means for supporting composition roofing in close contact with the cylinder so as to form the bottom of all the design sections in the rotation of

the cylinder, means for supplying grit or sand of different colors, and means for directing one color to one design opening and another color to another design opening so as to vary the color of the designs, substantially as described.

4. In combination with a cylindrical device 65 having designs formed by its periphery, a hopper for receiving the grit or sand of different colors to be applied to the composition roofing as it passes around the periphery of the cylinder, a partition in the hopper, and alternating openings in the hopper on opposite sides of the partition for feeding one color through one opening to one design section, and a different color through the opening on the opposite side of the partition to the adjacent design section, substantially as described.

5. In combination with a skeleton cylindrical device having means for rotating it, 70 means for supporting composition roofing in contact with the periphery and moving from a feeding to a receiving roll with the rotation of the cylindrical device, the said cylindrical device having a periphery made up of all open designs, with means for feeding to said designs colored sand or grit while the design section is in contact with the composition roofing so as to apply one color of sand or grit within the walls of the design section, and another color within the walls 75 of the adjacent section all from within the cylinder, substantially as described.

6. A feeding device for colored sand or grit to composition roofing, consisting of a hopper having a partition, openings from 80 each side of said partition, and rolls for feeding the material through the openings.

7. A feeding device comprising a hopper, 85 a partition therein, openings on opposite sides of the partition alternately arranged in relation to each other, rolls for feeding the material through the openings, and means for agitating the material, substantially as described.

8. In a machine for applying colored patterns or designs to composition roofing, supporting means for the roofing, and a traveling pattern device of approximately stenciled or open form adapted to regulate the feeding of different colored sand or grit 90 to the surface of the roofing, the design being determined by the shape of the openings, all of said patterns being supplied with sand or grit from the inside of the pattern device, substantially as described.

In testimony whereof, I affix my signature in presence of two witnesses.

ALEXANDER S. SPIEGEL.
